DESIGN FOR A COUNTER DISPLAY FOR PACKAGED COMMODITIES

Robert B. Wemyss, Louisville, Ky.

Application October 27, 1944, Serial No. 116,007

Term of patent 7 years

(Cl. D80—9)

To all whom it may concern:

Be it known that Robert B. Wemyss, a citizen of the United States, residing in Louisville, county of Jefferson, State of Kentucky, has invented a new, original, and ornamental Design for a Counter Display for Packaged Commodities, of which the following is a specification, reference being had to the accompanying drawing forming part thereof, wherein,

Fig. II is a side view thereof, in reduced scale.
I claim:

The ornamental design for a counter display for packaged commodities, substantially as shown.

ROBERT B. WEMYSS.
